UNITED STATES PATENT OFFICE.

EUGENE B. WHELAN, OF OMAHA, NEBRASKA.

COMBINED BY-PASS AND RELIEF VALVE.

1,353,296.

Specification of Letters Patent. Patented Sept. 21, 1920.

Application filed August 6, 1918. Serial No. 248,521.

To all whom it may concern:

Be it known that I, EUGENE B. WHELAN, a citizen of the United States, residing in the city of Omaha, county of Douglas, and State of Nebraska, have invented certain new and useful Improvements in Combined By-Pass and Relief Valves, and have described the same in the following specification, illustrated by the accompanying drawings.

My invention relates to that class of valves which are adapted to be used in steam engines of the piston-valve type, and individually to perform in such an engine, as occasion may require, the function of a by-pass valve and also the functions of a vacuum and compression relief valve. It is the main object of the invention to improve the construction and operation of valves of this class, especially the compression and relief valve for which Letters Patent of the United States were issued to me January 1st, 1907, under the Serial Number 839,912, and the combined vacuum and relief valve for which Letters Patent of the United States were issued to me and another November 25th, 1902, under the Serial Number 714,345; to use a single opening of the valve housing for the double purpose of constructively admitting the valve into the housing and of operatively relieving vacuum and compression, and thereby to reduce the number of openings in the housing and of exterior connections therewith; to provide the valve with a three-point bearing, and thereby prevent the same from moving laterally from its true path in the housing; to cushion the seating of the valve, and thereby prevent it from hammering; to provide externally visible means for observing the operative lift, or throw, of the valve, and thereby avoid disturbing or opening the housing for that purpose; to provide the valve with a special valve stop; and to adapt a valve of the specified class to operate as a by-pass valve and also as a relief valve in simple engines of the piston valve type, and in the several known types of compound steam engines, namely, the cross-compound, the four-cylinder compound, the tandem compound, the Mallet compound, and in all other multiple-expansion locomotive engines. To accomplish these objects, I incorporate in my improved valve, as parts thereof, a housing having two internal spaced valve seats, a double-seating puppet

valve co-acting with the valve seats, a top opening and a bottom opening from the housing to the external air and steam chest respectively, and an opening from the housing for communication with a steam cylinder, namely, either the boiler-pressure cylinder of the simple engine or a low-pressure cylinder of the compound engine, in which the invention is employed.

In said drawings, illustrating the best manner in which I have contemplated applying the principles of the invention, Figure 1 is a longitudinal vertical section of a steam engine having two duplicate combined by-pass and relief valves which are constructed in a preferred form, in accordance with these principles. Fig. 2 is a vertical longitudinal sectional view of one of the valves and valve housings of Fig. 1. Fig. 3 is a bottom view of the same valve housing. Fig. 4 is a longitudinal vertical sectional view of the same valve and valve housing in a modified form. Fig. 5 is a detail plan of a portion of Fig. 4. Fig. 6 is a horizontal section on the section line 6-6 of Fig. 8. Fig. 7 is a horizontal section on the section line 7-7 of Fig. 4. Fig. 8 is a detail vertical section of the valve on the section line 8-8 of Fig. 6.

In the illustrated specimens of my invention, the valve housing is denoted by the numeral 1. It has the spaced valve seats 2 and 3 disposed one above the other, for the double-seating valve 3. This valve is reduced intermediately of its seats *a* and *b*, or channeled, so that said seats operate only to close the escape-ways. Said valve is provided above its upper seat with an extension 4, working in the upper portion or extension 5 of the valve-housing. This housing extension has a cylinder-head 8, which is formed integrally therewith, an axial stem or boss, 6, which is threaded both externally and internally, and a plurality of spaced air-holes, 10, which extend radially through the cylindrical wall of the extension just below this head. The housing, being a unitary flat-bottomed metallic block, has an internal steam passage 7, which leads laterally from the valve chamber 9, and, like the valve chamber 9, extends down separately through the bottom of the block. It is bolted to the steam chest 11 and forms a steam-tight joint therewith. The housing extension 5 is provided with a cap 12, which

has a plurality of peripheral spaced holes 16 and a central axial hole 17 whereby it is fitted loosely upon the stem 6 and is rotarily adjustable thereon to bring said holes 16 into or out of complete registration with the air-holes 10 and thus to open the latter more or less, as may be required, or to close the same partly, but not entirely so as to hold more or less pressure within the head 18 and thus cushion the valve 3 on to its seats and prevent hammering. This cap is held in any position to which it may be so adjusted, by the nut 13 on the stem 6.

The valve chamber 9 communicates by the passage 14 with the chamber 15, which, in a single expansion engine, is the main high pressure steam channel to the cylinder 18, and, in the case of a multiple expansion engine, is the primary steam supply channel 20 to the second or subsequent expansion cylinder denoted by the same numeral 18. The steam passage 7 communicates with the cylinder by the channel 19. In the preferred form of the invention, the hollow cylindrical extension 25 under the seat 6 of the valve, has a plurality of radial steam passages 26, and works in the enlarged portion 27 of the valve chamber in sliding contact with the guiding ribs 28, down to and against, and is stopped by, the flat top of the steam chest. In the modification shown in Fig. 4, the joint ring 20 and the circular lift stop plate 21 are interposed between the valve housing and the steam chest. In this construction, the plate 21 has a plurality of perforating steam passages 22, overlaps the top margin of the passage 14, and has in the top of its elevated middle the flaring socket 23, which is adapted to receive 40 with centering, cushioning and stopping effect the coaxial boss 24 which projects from the bottom of the valve. In this construction as the boss 24 enters socket 23 the plate 21 affords a bearing for and lateral guidance to the valve, as do the ribs 28 of Fig. 4 in each instance cooperating with those portions of the valve housing above the valve seats to form a three-point bearing for the valve. This three-point bearing, together with the vertical disposition of the valve, as shown, effectively prevents lateral displacement, promotes more effective and sensitive operation, and reduces wear to a minimum so that the life of the valve in efficient condition is greatly increased.

The hollow stem 6 is ordinarily closed by the removable screw plug 29; when this plug is removed, the measuring rod 30 may be screwed into the top of the valve and 60 extend loosely through the stem 6, as shown in Fig. 4. Its reciprocating movement above the housing will then measure to the eye the operative throw or lift of the valve at that time. Thus, in operation, when the

locomotive throttle is closed, and the locomotive is drifting, both of the valves provided by my invention drop by gravity to open position, and the pressure is relieved from the space forwardly of the piston in either direction through the channels of the 65 valve housing, channels 19 and the steam chamber 15. In this way the pressure is simply by-passed from one side of the piston to the other side thereof, reducing the pressure in front of the piston and the vacuum in the rear thereof, in both directions of movement, and eliminating all drag so that the locomotive may drift freely. The act of thus by-passing the pressure furthermore accomplishes the desired result and 75 still maintains the steam chests and valve casing warm and in condition for most effective operation.

I claim as my invention—

1. In a valve of the type described, a casing having vertically spaced valve seats and adapted to be secured upon the flat top of a steam chest, a vertically movable valve member having portions co-operating with said seat and having guides slidably co-operating with portions of the casing, said casing having steam passages below the valve member and between the valve seats, and a plate interposed in the steam passage below the valve member, having a central 95 cavity and apertures around the cavity, the said valve member having a lower extension movable into the cavity of the said plate when the valve is in lowermost position.

2. A combined by-pass and relief valve 100 including a casing adapted to be bolted flatwise upon a steam chest, said casing having vertically spaced and aligned valve seats, and having steam passages one of which opens below the valve seats and the other of which 105 opens at one side of the first passage and extends between the valve seats, said casing having guide portions above its valve seats and upper adjustable valve cushioning means, a valve member having portions co-operating in vertically slidable relation with the guide portions of the casing and having valve pieces in vertically spaced relation shiftable into and out of engagement with the valve seats of the casing, and a 110 plate at the lower portion of the casing arranged to be clamped between the same and the flat top of a steam chest within the steam passage below the valve seats, said plate having openings therethrough and provided 115 with a central tapering socket, the valve member having a lower axially projecting and tapering boss arranged to enter the said socket of said plate when the valve member moves downwardly to open position.

Witness my signature at Omaha, Nebraska, August 2nd, 1918.

EUGENE B. WHELAN.
